UNITED STATES PATENT OFFICE.

GEORGE LESLEY, OF PERU, INDIANA.

BROODER.

Application filed November 20, 1922. Serial No. 602,084.

This invention relates to new and useful improvements in brooders.

The principal object of my invention is to provide a double-compartment brooder for chicks which is simple and economical in construction and superior to similar devices now on the market.

A further object of my invention is to provide a brooder which may be used outside and with equal success in summer or winter.

With the foregoing and other objects in view that will appear as the nature of my invention is better understood, the same consists in the novel features of construction, combination and arrangement of parts illustrated in the accompanying drawings and more particularly pointed out in the appended claim.

In the accompanying drawings, which are for illustrative purposes only and are therefore not drawn to scale:—

Figure 1 is a front elevation of a brooder, embodying my improvements.

Figure 2 is a horizontal section, taken on line 2—2 of Figure 1.

Figure 3 is a vertical longitudinal section, taken on line 3—3 of Figure 2.

Figure 4 is an end view of the brooder and Figure 5 a vertical transverse section, taken on line 5—5 of Figure 3.

Referring to the drawings for a more particular description of my invention and in which drawings like parts are designated by like reference characters throughout the several views, A designates the brooder which is of general rectangular form and divided into the upper and lower compartments B and C by the horizontal wall or partition D.

The upper compartment is divided into the larger and smaller compartments 1 and 2 by the transverse wall or partition 3, compartment 2 being used as a scratch pen for the chicks, and communicating with compartment 1 by the passage 4 in partition 3 normally closed by the sliding door 5.

The front wall of compartment 2 is provided with a screen 6 and the outer side wall 7 with a hinged door 8 normally held closed by the latch 9. The front wall of compartment 1 is provided with a hinged door 10, provided with a glass panel 11.

The lower compartment C is provided with a rectangular lamp housing E formed by the perforated end and side walls 12 and 13, respectively, in which is mounted the

lamp 14 of any ordinary or standard make. The front of the housing E is closed by the hinged door 15 which permits ready access thereto.

In carrying out my invention the lamp globe or chimney extends through an opening 17 in the horizontal wall or partition D and through an opening 18 in the bottom 19 of the earthen jug-shaped heating drum 20 mounted in compartment B over the lamp.

In practice, the fresh air first passes into the lamp housing E via the perforations in the side and end walls thereof, thence through the openings 17 and 19 into the earthen jug-like heating drum 20 and then through a series of vertical openings or vents 21 in the inner roof *a* of the brooder into the space *b* between the inner and outer roofs *a* and *c*, finally passing to the exterior or outside via the vents *d* at the ends of the brooder. The vent openings 21 are covered by the casing 22 of substantially semi-circular form in cross section and open at opposite ends, as shown. This casing prevents a direct draft from the mouth or neck 24 of the heating drum through the openings 21 and insures the proper circulation of the heated air in compartment B before passing to the outside or exterior of the brooder with the foul or vitiated air.

The chicks are first placed in the upper compartment and after three weeks may be removed to the lower compartment C as others are hatched.

From the foregoing description taken in connection with the drawings, it is thought that the construction, operation and advantages of my invention will be readily understood without requiring a more extended explanation.

Various changes in the form, proportions and minor details of construction may be resorted to without departing from the principle or sacrificing any of the advantages of my invention as defined in the appended claim.

Having described my invention, what I claim as new and desired to secure by Letters Patent, is:—

A brooder divided into upper and lower compartments by a horizontal partition, the roof of the brooder formed with a longitudinal series of vent openings and said partition formed with a vertical opening, a jug-like drum of heat resisting material

mounted in the upper compartment upon said partition, said drum formed in its bottom with an opening of less diameter than that in the partition and formed in its top 5 with a constricted outlet opening, a lamp mounted in the lower compartment with its chimney passing through the openings in the partition and bottom of the drum, a perforated housing in the lower compart-

ment enclosing the lamp and a horizontally 10 disposed hollow casing secured to the bottom of the roof of the brooder directly over the drum, said casing covering the vent openings and its opposite ends extending beyond the top of the drum.

In testimony whereof I affix my signature.

GEORGE LESLEY.
